UNITED STATES PATENT OFFICE.

BERNARD A. STERLING, OF CHICAGO, ILLINOIS, ASSIGNOR TO WESTERN HAIR GOODS CO., OF CHICAGO, ILLINOIS, A CORPORATION OF ILLINOIS.

FASTENING DEVICE.

Application filed December 17, 1926. Serial No. 155,366.

This invention relates to fastening devices, more particularly to fastening devices for use with hair dressing attachments, and the like, and its objects are the provision 5 of a generally improved and simplified device that may be economically produced and which will conform to the head and accommodate itself to and firmly grip different amounts of hair strands.

10 The device is adapted to be quickly and conveniently secured in place and removed and is adapted to be worn without discomfort to the head.

The invention is illustrated in the accompanying drawing, in which:

Figure 1 is an enlarged back or rear elevational view of a device embodying the present invention, showing a hair piece attached thereto;

20 Figure 2 is a front elevational view of the fastening device;

Figure 3 is a side elevational view;

Figure 4 is a transverse section taken on the line 4—4 of Figure 1;

25 Figure 5 is a fragmentary longitudinal section taken on the line 5—5 of Figure 1; and

Figure 6 is a front elevational view of the prong member.

30 Referring to the drawing, the embodiment of the invention shown comprises a base 5 having a prong member 6 pivoted to one end of the base and adapted to be sprung into and out of engagement with a catch 7 on the base.

The base 5 may be of suitable sheet metal and is preferably curved as shown at 8 in Figure 3 to conform to the head. As it is formed the base 5 has a pair of tabs 10

40 separated centrally and extending longitudinally from opposite sides of one end of the base as shown in dotted lines in Figure 2. These tabs 10 are rolled back and form pivot knuckles 12 (Figures 1 and 3) for the prong member 6.

The front or prong side of the base 5 has a hump 14 extending longitudinally of the base and centrally between the opposite sides thereof. This hump 14 may be pressed up from the back side of the base. It cooperates with the prong 6 and, in addition, reinforces the base 5 and imparts a desired rigidity thereto against being bent or deformed from its desired curvature.

55 Also centrally disposed between the op-

posite sides of the base 5 and longitudinally beyond the end of the hump 14 and in alignment therewith is the catch 7. This catch 7 is in the form of a stud or button projecting at substantially right angles from the front side of the base 5 and provided with an annular groove 16 forming a head 18 past which and into and from the groove 16 the prong 6 is adapted to be sprung. The catch 7 may be riveted or otherwise 60 suitably secured to the base 5.

The prong 6 is also curved to conform to the head and is preferably formed of suitable spring wire looped or doubled back into somewhat generally U formation with

70 the free ends of the wire disposed at one end of the prong and turned laterally at 20. The prong 6 is contracted near one end at 21 between the laterally turned ends 20 and the generally parallel sides 22 and near its opposite end the sides 22 may be contracted at 23 for cooperation with the catch 7. The prong 6 may be additionally contracted outwardly of the contracted catch engaging portion 23 or it may be otherwise formed 75 to provide a finger piece 24 which may be conveniently grasped to spring the prong into and out of engagement with the catch 7.

The laterally turned ends 20 of the prong 80 fit in the knuckles 12 and pivotally mount 85 one end of the prong upon the base 5. The sides of the prong 6 may be bound together at the contracted portion 21 by a cross piece 26 looped at its opposite end about the sides of the prong and rigidly 90 pressed thereon to hold the sides against springing together at the pivot and the laterally turned ends 20 against displacement from the knuckles 12.

95 Fitting over and reinforcing the side portions 22 of the prong 6 is a sleeve 30 in the form of a short length of tubing of relatively tough rubber or other material preferably of resilient and anti-slip character. The sleeve or tube 30 is drawn over the side 100 portions 22 of the prong from the contracted end 24 and is tensioned thereby so that its resiliency draws the side portions 22 and the contracted portions 23 together 105 so that the contracted portions 23 will not pass over the head 18 of the catch 7 without the sides of the prong spreading apart. The head 18 is preferably rounded at 32 to engage between and spread the contracted sides 23 as the prong is closed toward the 110

base 5, and then as the contracted side portions 23 pass over the head 18 they are contracted by the rubber tube 30 and by their own springiness into the groove 16 and the 5 prong is thereby locked in closed position against the base 5.

The side portions 22 of the prong 6 straddle the hump 14 which, when the prong is closed, presses against the band or sleeve 30. 10 The sleeve 30, because of its resilient character, gives or yields to the hump 14, so that different amounts of hair strands may be accommodated between the base 5 and the prong 6, and the device will accommodate itself thereto and grip a few or relatively large number of strands of hair equally as well.

In use the device is inserted up into the hair with the back side presented to the head 20 and the prong opened to permit a mass of hair strands to pass between the base 5 and the prong 6. The prong is then swung into closed position and the contracted side portions 23 are sprung over the head 18 of the 25 catch or button 7 and into the groove 16, whereupon the free end of the prong is locked to the base with the strands of hair firmly clamped between the prong and the base.

30 In addition to reenforcing, and drawing the sides of the prong together, the band or rubber sleeve 30, because of its yieldable and anti-slip character, binds the strands of hair firmly and positively and prevents accidental slipping of the device after it is attached to the hair.

While the device may, of course, be employed wherever found desirable, it is particularly adapted for attaching hair pieces 40 upon the head and to the natural hair of the user. For this purpose the base 5 has longitudinal rows of apertures 38 on opposite sides of the hump 14 and the catch 7 through which the wefted end of the hair piece 40 may be secured to the base 5, as by stitching 45 42 passing through the apertures 38 and stitched to the adjacent end of the hair piece.

It is to be understood that in actual practice in attaching a hair piece, or the like, 50 the device is not as large as illustrated, the enlargement in the drawing being merely to clarify the disclosure.

The device may be arranged crosswise of the end of the hair piece 40, as shown, or 55 otherwise as desired.

Furthermore, the contracted portion 23 of the prong member 6 may be adapted to pass freely over the catch 7, until the sleeve 30 is placed over the prong and the sides of the 60 prong may be contracted by the sleeve 30 when it is placed thereon, so that the portion

23 is thereafter sprung over and from the catch 7.

I claim:—

1. As an article of manufacture, a fastening device comprising a base member, a catch on said base member, a hump on said base member, a prong pivoted on said base member and having a pair of side portions adapted to straddle said hump and engageable with said catch, and a single resilient sleeve embracing both side portions of the prong along said hump for yieldable cooperation with the hump centrally between the side portions of the prong. 65 70 75

2. As an article of manufacture, a fastening device comprising a base member, a catch on said base member, a hump on said base member, a wire prong doubled back with its free ends turned laterally and pivoted in knuckles on the base member, the sides of the prong adapted to straddle the hump on said base member and being contracted along the catch to be sprung over and from said catch, and a single resilient sleeve embracing both of the sides of the prong along the hump and between the contracted catch engaging and laterally turned pivoted portions of the prong for yieldable cooperation with the hump centrally between the sides of the prong. 80 85 90

3. As an article of manufacture, a fastening device comprising a base member, a button catch on said base member having a head and reduced between the head and the base member, a hump on said base member, a wire prong doubled back and pivoted on said base member at its free ends, said prong having side portions adapted to straddle said hump and contracted outwardly of said hump straddling portions to be sprung over and from the head of said catch, and a rubber sleeve embracing both side portions of the prong along the hump, said sleeve opposing spreading of the catch engaging portions of the prong and cooperating with said hump to bind the device upon the strands of hair. 95 100 105

4. As an article of manufacture, a fastening device comprising a base member, a catch on said base member, a hump on said base member, a prong pivoted on said base member and having a pair of side portions adapted to straddle said hump and engageable outwardly of said hump with said catch and a single resilient sleeve embracing both side portions of said prong for yieldable cooperation with the hump therebetween and opposing spreading of said side portions. 110 115

In witness whereof, I hereunto subscribe my name this 13th day of December, 1926.

BERNARD A. STERLING.
